(57) **CLAIM**

The ornamental design for an apparatus for processing proteins, as shown and described.

DESCRIPTION

FIG. 1 is a perspective view of the apparatus for processing proteins showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Any broken line illustration of environmental structure in the drawings is not part of the design sought to be patented.

The broken lines are included for the purpose of illustrating unclaimed portions of the apparatus for processing proteins and form no part of the claimed design.
